(57) **CLAIM**

We claim the ornamental design for an in-cord load control device, as shown and described.

DESCRIPTION

FIG. 1 is a front perspective view of an in-cord load control device according to our new design.

FIG. 2 is a front elevation view thereof.

FIG. 3 is a left side elevation view thereof.

FIG. 4 is a right side elevation view thereof.

FIG. 5 is a top plan view thereof.

FIG. 6 is a bottom plan view thereof.

FIG. 7 is a rear perspective view thereof; and,

FIG. 8 is a rear elevation view thereof.

The portions of the drawings appearing in broken line show unclaimed subject matter only and do not form a part of the claimed design.
